UNITED STATES PATENT OFFICE

145,098

DESIGN FOR A SCARF OR SIMILAR ARTICLE

John William Morrison, Garden City, N. Y., assignor to Martex Print Works, Inc., Clifton, N. J., a corporation of New Jersey

Application February 14, 1946, Serial No. 126,565

Term of patent 14 years

(Cl. D3—12)

To all whom it may concern:

Be it known that I, John William Morrison, a citizen of the United States of America, residing at Garden City, in the county of Nassau and State of New York, have invented a new, original, and ornamental Design for a Scarf or Similar Article, of which the following is a specification, reference being had to the accompanying drawing, forming part thereof.

In the drawing the single figure is a plan view of a scarf or similar article, showing my new design.

I claim:

The ornamental design for a scarf or similar article, as shown.

JOHN WILLIAM MORRISON.
